MINE DOOR STRUCTURE

Boyd Mullins and Arthur Randolph Brown,
Keystone, W. Va.

Application September 5, 1934, Serial No. 742,842

6 Claims. (Cl. 246—304)

This invention relates to an improved mine door structure of the so-called mechanical automatically operable type, that is the form wherein in a pair of complementary doors are mounted to swing in a horizontal plane on a vertical axis and are susceptible of being swung to open position by the cars as they pass back and forth through the tunnel.

It is generally well known that in mine tunnels it is customary to provide closures or doors at predetermined intervals in order to close the tunnel for the purpose of controlling and deflecting the air usually employed for ventilating the mine. These doors serve to divide the tunnel into individual runways and to shunt the air from a main passageway to a branch passageway or tunnel in a well known manner.

We are aware of the fact that numerous forms of door constructions have been developed to accomplish the desired results and it therefore follows that by way of contrast we have evolved and produced an improved structure characterized by noteworthy refinements and distinctions calculated to enable the invention, as a whole, to better perform the anticipated result and to fulfill the requirements in a satisfactory and dependable manner.

As will be evident from the succeeding description and accompanying illustrative drawings the principal novelty is predicated upon the bumpers or buffers on the companion doors, together with the hinge mounting for the doors and the guiding and return means especially devised to insure efficient opening and closing of the doors.

Other features and advantages will become more readily apparent from the following description and drawings.

In the drawings:

Figure 1 is a view in section and elevation showing the preferred embodiment of the invention, the doors being swung to closing position.

Figure 2 is a horizontal sectional view of the structure illustrated in Figure 1.

Figure 3 is a detail view in elevation and section disclosing an especially designed guide arm.

Figure 4 is an end view illustrating the general shape and position of the guide rails or tracks.

Figure 5 is a view in section and elevation illustrating the door hinge, or mounting.

Figure 6 is a view in section and elevation showing the adjoining ends of the associated track rails and the manner in which the guide roller cooperates therewith.

Referring now to the drawings by distinguish-

ing reference numerals it will be observed that the numeral 7 designates either the mine tunnel or an enclosure in said tunnel or passageway to accommodate car tracks 8. For the purpose of accommodating features of the invention this enclosure is shown in Figure 2 as provided with a pair of opposed V-shaped extensions 9 to prevent air leakage and to accommodate certain of the parts of the structure. It is evident, however, that this housing or enclosure may be of any appropriate construction. As a matter of fact in less thorough constructions the door structure can be mounted in the tunnel without protective and guard means. It is preferred however to use the structure illustrated in the drawings.

The doors, which may be of any dimension and material, are denoted by the numerals 10 in Figure 1. Inasmuch as both doors and the associated mechanism is the same in each instance a description of one will suffice for both. It is understood, however, that the door and their complementary parts are arranged opposite each other that is in pairs so as to provide the desired transverse closure for the tunnel.

Directing attention at this time to Figure 5 it will be observed that the door is provided on opposite sides and adjacent its bottom with duplicate semi-oval guards 11. These serve as bumpers or buffers and when properly in position define a substantially oval shaped bumper whose sections 11 serve to permit the door to be swung open in either direction, that is irrespective of the movement of the car along the track. The numeral 12 designates a vertical post and the numeral 13 designates a surrounding tube or sleeve carried by the door and mounted for oscillation on said post. This provides the desired vertical hinge structure for the horizontally swingable door. It will be further noted that the oscillatory sleeve is provided with diametrically opposed projection 14 carrying headed studs 15. These studs serve as pivotal connections for the arms of a yoke 16 carried on the inner end of the two-way drag and guide arm 17. This arm is in the nature of a rod as shown in Figure 3 and on its free end is provided with an anti-friction roller 18 which functions as a shoe. This shoe is adapted to run back and forth on one of the guide rails 19. There are two of these rails as shown in Figure 4 and they extend outwardly with their free ends properly shaped and bent and suitably anchored. The rails curve gradually upwardly and then inwardly so as to allow the roller 18 on the arm 17 to swing in the desired arc or path as the door swings from

shut to open position and then back to closed position. It will be noticed in Figure 5 that the oscillation of the sleeve 13 carries the arm 17 with it. The arm however has an up and down direction of movement that is substantially perpendicular so that it can follow the contour or shape of the complementary guide rails. It will be further noted in Figure 6 that the inner ends of the two rails come together in V-shaped form as indicated at 20 and this forms a sort of a keeper or seat in which the roller drops when in centralized or neutral position. This arrangement also allows the roller to ride up on the rails, that is either rail according to the direction of movement of the associated door. It is evident therefore that we have a swingable door provided with bumpers 11 wherein said door is hingedly mounted by a sleeve or equivalent device 13 on the post 12. The sleeve carries a drag link or arm 17 having an anti-friction shoe at its free end movable along opposed complementary guide rails. The guide rails and arm 17 are located in the V-shaped extension of the enclosure as depicted in Figure 2 of the drawings. If desired the enclosure structure may include a pair of spaced parallel walls 21 which function as a partition and guard in which the arm 17 comes to rest, that is in its normal centralized position. When this boxing arrangement is employed it is necessary to provide hinged closures 22 as shown in Figure 6 so as to provide effective air protection means.

We now call attention to the counterweight cable and pulley assemblage shown in Figure 1. To begin with numeral 23 designates a post or standard mounted between the walls 21. This carries a pulley 24 over which the cable 25 is trained, the free end of the cable being attached by a collar or bracket 26 to the intermediate portion of the adjacent swingable arm 17. Then the cable extends up and over a second guide pulley 27 and on the free end of the cable is a counterweight 28. It is evident therefore that as the car comes into contact with the bumper it rides in a cam-like manner on the bumper and forces the door open against the retention action of the counterweight 28. This lifts the weight up and places the door under a return strain so that as the car passes beyond the door the counterweight, in an evident manner closes the door through the instrumentality of the cable and pulley arrangement and arm 17. As before stated the arm 17 has a two-way movement so as to allow it to accommodate the shoe and guide rail means.

It is evident from the drawings and description that novelty is predicated in one instance on the particular door and bumper construction which arrangement is calculated to operate freely and effectively. Secondly novelty is predicated upon the hinge mounting illustrated in Figure 5 of the drawings together with the yoke 16 and drag rod or arm 17, and the features 14 and 15 which provide for the requisite movement of the arm 17 in order to accomplish effective stabilized opening and closing of the door. Finally novelty is attached to the cable and pulley and weight arrangement shown in Figure 1 which, it is believed, satisfactorily performs its appointed task and does this in a reliable manner.

It is thought that persons skilled in the art to which the invention relates will be able to obtain a clear understanding of the invention after considering the description in connection with the drawings. Therefore, a more lengthy description is regarded as unnecessary.

75 Minor changes in shape, size, and rearrange-

ment of details coming within the field of invention claimed may be resorted to in actual practice, if desired.

Having thus described our invention, what we claim as new is:

1. In a structure of the class described, a fixed vertical support, a sleeve mounted for oscillation on said support, a door attached to said sleeve, bumpers on said door, said sleeve being provided with headed studs, a guide arm having yoke members pivotally connected with said studs to cause the arm to swing in a horizontal plane and to allow it to have vertical movement as well, said arm being provided with an anti-friction roller, and a pair of relatively stationary guide rails with 15 which said roller cooperates.

2. In a structure of the class described, a fixed vertical support, a sleeve mounted for oscillation on said support, a door attached to said sleeve, bumpers on said door, said sleeve being provided 20 with headed studs, a guide arm having yoke members pivotally connected with said studs to cause the arm to swing in a horizontal plane and to allow it to have vertical movement as well, said arm being provided with an anti-friction roller, 25 and a pair of relatively stationary guide rails with which said roller cooperates, a cable, a plurality of pulleys over which said cable is trained, said cable being attached at one end to the arm, and counterweight means on the free opposite end of 30 said cable.

3. In a structure of the class described, a fixedly mounted vertical post, a door having a sleeve mounted for oscillation on said post, said sleeve being provided with diametrically opposed headed 35 studs, bumpers on said door, a guide arm having a yoke pivotally attached to said studs, a roller on the free end of said arm, guide rails fixedly mounted, said roller being cooperable with said guide rails, a stationary standard, a pulley on said 40 standard, a cable trained over said pulley and attached at one end to said arm, a second pulley, said cable being trained over said second pulley, and said cable being provided on its free end with a counterweight.

4. In a structural assemblage of the class described, a fixedly mounted vertical post, a door equipped with a sleeve mounted for oscillation on said post, a guide arm pivotally attached at its inner end to said sleeve in a manner to cause 50 said arm to swing with the door and sleeve while simultaneously moving in a vertical plane, an anti-friction shoe on the outer end of said arm, a fixed standard arranged adjacent to said post, a pair of companion track rails fixedly secured 55 at their inner ends to said standard, said shoe being engageable with and movable outwardly and inwardly along said rails, a pulley mounted on said standard, a cable attached at its inner end to the arm adjacent said shoe, said cable 60 being trained over said pulley, a second pulley fixedly mounted at an elevation above said first named pulley, the free end portion of said cable passing over said second pulley, and a counterweight on the free end of said cable.

5. In a structural assemblage of the class described, a fixedly mounted vertical post, a door equipped with a sleeve mounted for oscillation on said post, a guide arm pivotally attached at its inner end to said sleeve in a manner to cause 70 said arm to swing with the door and sleeve while simultaneously moving in a vertical plane, an anti-friction shoe on the outer end of said arm, a fixed standard arranged adjacent to said post, a pair of companion track rails fixedly secured 75

- at their inner ends to said standard, said shoe being engageable with and movable outwardly and inwardly along said rails, a pulley mounted on said standard, a cable attached at its inner end to the arm adjacent said shoe, said cable being trained over said pulley, a second pulley fixedly mounted at an elevation above said first named pulley, the free end portion of said cable passing over said second pulley, a counter-weight 10 on the free end of said cable, and a protective enclosure for said standard, arm, pulleys and cable, said enclosure including a partition made up of spaced parallel walls disposed on opposite sides of the standard and its complemental features.
- 15 6. In a mine door construction of the class described, a protective enclosure including a pair of opposed end extensions having vertical oppositely located partitions, said partitions being made up of spaced parallel walls, vertical posts mounted in the enclosure at the inner vertical ends of said partitions, a pair of bumper equipped car actuated doors mounted on said posts in complemental alignment, standards mounted in the partitions between the adjacent pairs of walls, guide rails attached to the standards, arms connected with and swingable with said doors and having drag 10 means cooperable with said guide rails, said standards having pulleys, and cables attached to the arms and cooperable with said pulleys.

BOYD MULLINS.

ARTHUR RANDOLPH BROWN.
